LIFE BOAT

Ane Pieter Schat, Utrecht, Netherlands

Application June 17, 1931, Serial No. 545,087. Renewed August 23, 1935. In Great Britain June 21, 1930

12 Claims. (Cl. 9—22)

It has been proposed to provide a life boat with skate-like members adapted to be clamped to and detached from the boat, said members having for their duty to guide the boat during launching over the ship's side and to reduce the contact surface between the ship's hull and the boat to the smallest possible area. Reference is had, inter alia, to my prior British Patent specifications Nos. 252,014, 255,727, 257,300 and 259,148.

I now suggest constructing a life boat in such a manner that the skate-like members, or substantial portions thereof, form integral parts of the boat. For instance, the boat may be provided with two frame-like outer rims suitably spaced apart and extending athwart from one gunwale to the other. Said rims may be separate members riveted or otherwise secured to the sides of the boat, or they may be formed by suitably bending or flanging the sheets or other elements of which the boat is made. In the latter case the boat may be composed of a tapering front portion, a preferably straight central portion and a tapering rear portion, said portions being provided with outwardly directed flanges by means of which they are assembled through rivets, bolts or any other suitable fastening means, or, in case of a steel boat, by welding. Packing material may be interposed between said flanges.

A boat constructed as indicated can be launched on either side of the vessel.

My novel construction is more especially intended for steel boats, but can also be used in connection with boats made of other material, for instance, so-called vulcan fibre, prepared by saturating a kind of filter paper with zinc chloride, and thereupon washing and drying the product.

I am aware that a life-boat provided with skate-like members forming integral parts thereof may not be as navigable as an ordinary boat, but this is no consideration since in case of a casualty life boats should not move from the spot but await the arrival of steamers called to rescue by radio.

Reference will now be made to the accompanying drawing which represents an all-metal life-boat constructed in accordance with my invention:

Figure 1 is a plan view of the boat,

Figure 2 a cross section of the boat at its middle portion,

Figure 3 a section taken on the line A—B in Figure 2, looking in the direction of the arrows.

The keel 1 of bulb section is at its ends 2 bent upwards so as to form the stem and stern of the

boat. At right angles to the keel and connected thereto, for instance, by riveting, but preferably by welding, are the skates 3, 4, 5 and 6, equally of bulb section and forming with the keel a frame construction, to which the hull plates 7, 8, 9, 10, 11 and 12 are secured by means of flanges, preferably welded to the frame members. In order to reduce the resistance of the boat when towed through the water, the spaces on either side of the skates, i. e. between these parts and the boat's hull are filled up with wooden blocks 13, 14, 15, 16 of triangular or other suitable cross section. The relatively small strength of a steel boat to withstand crashing against the side of the ship from which it is being launched, may be materially increased by means of a preferably resilient structure of flat or shaped iron or steel as at 17 and 18, connecting the skates 3, 4 and 5, 6 respectively, or riveted, welded or otherwise secured to the inner faces of the boat's hull. 20

For use in connection with a boat construction as described having a boat chock according to my co-pending patent application No. 436,558, I provide a cradle as shown in Figures 2 and 3, consisting of two plates 19 provided with flanges 20, to suit the wooden blocks 14 on either side of the skate 4, and interconnected by means of screw bolts and distance pieces 21, between which plates are mounted rollers 22, 23 running on the chock or guide way 24, sloping to the outside of the vessel. 30

To prevent the boat as well as the cradle from unduly sliding down the chock 24, I connect the cradle by means of a rope 25, provided with a slip-hook 26 to the vertical section iron 27 supporting the inboard side of the chock and connected by means of an angle iron 28 to the ship's deck 29. For launching the boat it is only necessary to loosen the slip hook 26 and a corresponding slip hook in the plane of the skates 5 and 6, after which the boat and the cradle are free to slide down-hill towards the water. The cradle after passing the sheer strake of the vessel falls free from the boat, but may be hauled inside the boat by means of a rope 30, connecting the cradle and the skate 4. 40

In some instances the skate-like members integral with the boat may form only part of the complete skate. For instance, I may rivet to the outside of the boat two angle irons with their 50 upstanding flanges spaced a small distance apart so as to form a groove for receiving the skate proper in the shape of a flat strip having a bulb along its outer edge. Said skate may then be arranged to be detachably connected to the boat 55

in any known or convenient manner. It will be understood that the said angle irons are a means for supporting the skate proper on both sides and for preventing the same from being displaced sideways under the influence of impacts that may act thereon. The corners formed between the angle irons and the boat's hull may again be filled up with wooden blocks or the like having a triangular or other suitable cross section.

10 What I claim is:

1. A life-boat provided with skate-like members for guiding the boat over the side of the vessel from which it is launched, said members forming integral parts of the boat, said boat being provided at its inside with a resilient structure interconnecting the skate-like members on either side of the boat.
2. A life-boat comprising a central section and stem and stern sections, and having on either side skate-like members for guiding the boat over the sides of the vessel from which it is to be launched, said members forming integral parts of the boat, and being rigidly connected to the central section thereof, said section being provided at its inside with a yielding structure extending athwartships and interconnecting the skate-like members on either side of the boat.
3. A life-boat comprising a central section and stem and stern sections, and provided with skate-like members for guiding the boat over the side of the vessel from which it is launched, said members forming integral parts of the boat, and rigidly connected to the central section thereof, said boat being provided at its outside with blocks filling up the corners between the skate-like members and the boat's hull.
4. A life-boat comprising a central section and stem and stern sections, and provided with skate-like members for guiding the boat over the side of the vessel from which it is launched, said members forming integral parts of the boat and rigidly connected to the central section thereof, in which boat the keel is made of iron and is integral with the stem and the stern, the skate-like members being secured to the keel to form a frame to which sections of the boat's hull are mounted.
5. A life-boat comprising a central section and stem and stern sections, and provided with skate-like members for guiding the boat over the side of the vessel from which it is launched, said members forming integral parts of the boat, and rigidly connected to the central section thereof; a cradle for use in connection with said life-boat and combined with a boat chock sloping down in outboard direction, said cradle consisting of a pair of plates, screw bolts and distance pieces, said plates being adapted to support the boat on either side of any one of the skate-like members, said plates being interconnected by means of said screw bolts and distance pieces.
6. A life-boat comprising a central section and stem and stern sections, and provided with skate-like members for guiding the boat over the side of the vessel from which it is launched, said members forming integral parts of the boat, and rigidly connected to the central section thereof; a cradle for use in connection with said life-boat and combined with a boat chock sloping down in outboard direction, said cradle consisting of a pair of plates, screw bolts, distance pieces and rollers, said plates being adapted to support

the boat on either side of any of the skate-like members, said plates being interconnected by means of said screw bolts and distance pieces, and provided with rollers therebetween.

7. A boat consisting of a frame and a hull rigidly secured thereto, said frame including opposing transverse members connected at their lower ends to the keel of the boat and curving outwardly and upwardly therefrom to the top of the boat, and having interconnecting braces at their upper ends, said curved members projecting out beyond the hull of the boat and being formed into skates for the boat; whereby said skates are an integral part of the boat.

8. A boat consisting of a frame and a hull rigidly secured thereto, said frame comprising a keel extending from stem to stern of the boat; opposing transverse members secured at their lower ends to said keel and curved outwardly and upwardly therefrom to the top of the boat; and a transverse brace interposed between the upper ends of said outwardly and upwardly curved members, said curved members projecting outwardly beyond the hull of the boat with their projecting portions formed into skates for the boat; whereby the skates form integral parts of the frame.

9. A lifeboat comprising stem and stern sections and an intermediate section; and skate-like members rigidly connecting said members together and arranged to guide the boat over the sides of the vessel from which it is launched.

10. A lifeboat comprising stem and stern sections and an intermediate section; and skate-like members for guiding the boat over the sides of the vessel from which it is launched, said component parts of the boat being rigidly connected together, and said skates being located at the junctions of said parts.

11. A boat consisting of a frame having integral longitudinal and transverse members, and a hull rigidly secured thereto, said integral transverse frame members projecting outwardly beyond the hull at both its bottom and sides to form integral portions of the frame for undergirding the hull of the boat while at the same time forming integral skates therefor, said skates having convex working faces disposed in vertical planes at right angles to the longitudinal extent of the boat and of the ship with which the boat is to be used, and designed to ride downwardly on the convex outer side of a listed ship as the boat is lowered from the ship's deck to the water.

12. A boat consisting of a frame having integral longitudinal and transverse members, and a hull rigidly secured thereto with said integral transverse frame members projecting outwardly beyond the hull at both its bottom and sides to form integral portions of the frame for undergirding the hull of the boat while at the same time forming integral skates therefor, the bottom of the hull on either side of the longitudinal centre thereof, and the lower portions of the respective skates contacting therewith, being arranged when viewed transversely, to approach a straight line with the parts on the two sides of said centre extending downwardly-and-inwardly toward each other, each of said parts forming an angle less than a right angle with the vertical plane extending longitudinally through the keel of the boat.

ANE PIETER SCHAT.
